L. J. BLADES, JR.
CASE OR RACK FOR DISPLAYING PAMPHLETS, PRINTED FORMS, AND LIKE MATTER.
APPLICATION FILED MAR. 20, 1915.

1,254,766.

Patented Jan. 29, 1918.

UNITED STATES PATENT OFFICE.

LEONARD J. BLADES, JR., OF CHICAGO, ILLINOIS.

CASE OR RACK FOR DISPLAYING PAMPHLETS, PRINTED FORMS, AND LIKE MATTER.

1,254,766.

Specification of Letters Patent. Patented Jan. 29, 1918.

Application filed March 20, 1915. Serial No. 15,876.

To all whom it may concern:

Be it known that I, LEONARD J. BLADES, Jr., a citizen of the United States, residing at Chicago, in the county of Cook and State of Illinois, have invented certain new and useful Improvements in Cases or Racks for Displaying Pamphlets, Printed Forms, and like Matter, of which the following is a specification.

10 My invention has reference to holders for exhibiting folders, pamphlets, booklets, tablets or similar printed matter, and has for its object the production of a simple, practicable case in which the partitions shall be 15 adjustable in width to provide for the reception and display of a variety of such articles of varying widths. The invention relates especially to the construction and arrangement of the partitions with respect to 20 the frame of the case, and its novelty will be more particularly pointed out in the appended claims.

In the drawings Figure 1 represents a 25 vertical section on the line 2—2 of Fig. 2, of a case of well known form and arrangement, such as is commonly used for the display of railway time tables, in which my invention is embodied; Fig. 2 is a front view of one tier of compartments of such case, 30 the flanges of the retaining groove being broken away a short distance at the right hand partition to better show a slightly modified form of attaching plate for such partition; Fig. 3 is a perspective of one 35 of the partitions alone; Fig. 4 is a fragmentary section on the line 4—4 of Fig. 2; Fig. 5 is a front or face view of a modified form of partition; Fig. 6 is a fragmentary section of such modified form on the line 6—6 40 of Fig. 5; Fig. 7 is a perspective of the same; and Fig. 8 is a perspective of an implement suitable for turning the locking disk of the form of partition shown in Figs. 5 to 7.

45 The same reference figures indicate the same parts in the several figures of the drawing.

Referring to the form of case illustrated 50 in the drawings, the sections of the case are arranged in tiers rising one above the other from front to rear, each section comprising a back wall 1, a bottom 2, a front rail 3 (which may be formed separate or may be 55 integral with the bottom, as shown), and ends 4, 4. In the back wall of the back

of the section is arranged a retaining groove, which in the present instance is formed by a strip of sheet metal 5 having inwardly bent flanges 5^a and seated in a recess in the back wall.

The detachable and adjustable partitions 6, of which any number may be used, are each formed with an attaching plate or base 7 extending at right angles to the partition itself, in the present instance this base being formed of an integral extension of the sheet metal plate constituting the partition and being connected with such partition by a broad tongue. The width of the base between the tongue and the edge opposite it is less than that of the space between the flanges of the retaining groove, and its height is greater and of such dimensions as to snugly enter and fit within the groove beneath the flanges 5^a when the partition is in upright position in the case.

One of the horizontal edges of the attaching plate, in the present instance the lower edge, is bent, as along the line 8, in such manner that the plate will resiliently 80 and frictionally engage the top and bottom of the retaining groove under the flanges 5^a. Two diagonally opposite corners of the attaching plate are clipped diagonally—or they may be rounded off, see the right hand 85 plate in Fig. 2—the shape and proportions of the coacting parts being such that the partitions may be applied or attached to the sections at whatever points desired by turning any partition sidewise to an angle of 90 about forty-five degrees from the perpendicular, and inserting its base within the retaining groove, and then turning the partition to upright position, the top and bottom marginal portions of the base engaging the groove frictionally under the flanges 5^a and maintaining the partition in adjusted 95 position. As shown in dotted lines in Fig. 2, the perpendicular distance between the clipped corners when the attaching 100 plate is turned angularly sidewise is slightly greater than the opening between the flanges of the groove, but the neck between the partition and base is narrow enough to permit one corner to be slipped under the adjacent 105 flange a sufficient distance to permit the opposite corner to clear its flange and thus be inserted under it.

Slightly below the horizontal plane of the tops of the partitions, when adjusted in up- 110

right position, is arranged a horizontal rod 9 fixed at its opposite ends to the sides of the section near their front edges and lying within inclined slots 10 extending downwardly and forwardly from the top edge of each partition near its upper forward corner. This rod and the rail 3 at the bottom of the section serve to retain the matter between the partitions from falling out forwardly, and the inclination of the slots prevents the rod from being bowed and yielding upwardly out of disengagement with the slots when the compartments are packed tightly with matter, as would be apt to occur were the slots made vertical.

In the modified form of my invention shown in Figs. 5 to 7, the means for securing the base of the partition in the retaining groove 5 consists of a disk 11 eccentrically mounted on a pivot 12 on the base near its upper edge, and which may be rotated to jam against the top of the upper portion of the groove underlying the upper flange 5^a, thus locking the partition in place. 20 To facilitate rotation of the disk, for the purpose of causing its engagement and disengagement in the retaining groove, a central hole 13 is formed in the disk, and a suitable tool is provided adapted to engage 25 within such hole and bear against the head of the pivot 12 (which is formed to project for the purpose), so that by the rotation of the tool the disk can be turned.

I have also illustrated in Figs. 5 to 7 a 30 further modification of my invention, which may, however, be used with the attaching means shown in Figs. 1 to 4. In this modification, for the purpose of retaining the matter within the compartments, each partition has rigidly secured to it a short transverse rod passing through it near its upper front corner, the slot 10 and transverse rod 9 being of course not used.

While my invention is well adapted for 40 use in connection with ordinary forms of display racks or cases for the exhibition of railway time tables and similar folders, it is obviously also adapted for use in cases of varying proportions and arrangement 45 for holding blank forms or tablets of various sizes, such as are used in banks and many commercial or manufacturing establishments, and for the display of advertising pamphlets or other matter of many 50 kinds.

I claim:

1. In a structure of the character described, a horizontal casing section arranged for the reception of articles to be displayed, 55 said section being provided with a retaining groove extending longitudinally along the rear wall thereof, and vertical partitions each provided with a base adapted to make locked engagement restraining sliding movement at any point in said retaining

groove when turned from an inclined to a vertical position at right angles to a plane passing vertically through the groove.

2. In a structure of the character described, a horizontal casing section arranged 70 for the reception of articles to be displayed, said section being provided with a retaining groove extending longitudinally along the rear wall thereof and formed with overhanging flanges at its opposite sides, and 75 vertical partitions each provided with a base adapted to enter said retaining groove between the flanges when applied thereto at a determined angular position and enter into and make frictional engagement with in the groove underneath the flanges restraining sliding movement when the partition is turned to bring it into vertical position at right angles to a plane passing vertically through the groove.

3. In a structure of the character described, a horizontal casing section arranged for the reception of articles to be displayed, said section being provided with a retaining groove extending longitudinally along 90 the rear wall thereof and formed with overhanging flanges at its opposite sides, and vertical partitions each provided with a sheet metal base of a length adapted to permit its insertion between the flanges 95 measured in a direction at an angle of approximately forty-five degrees to the partition and of a length adapted to prevent its withdrawal from between the flanges measured in a direction parallel to the partition.

4. In a structure of the character described, a horizontal casing section arranged for the reception of articles to be displayed, said section being provided with a retaining groove extending longitudinally along the rear wall thereof and formed with overhanging flanges at its opposite sides, and vertical partitions each provided with a sheet metal base of a length adapted to permit its insertion between the flanges measured in a direction at an angle of approximately forty-five degrees to the partition and of a length adapted to prevent its withdrawal from between the flanges measured 105 in a direction parallel to the partition, said base being bent to constitute portions lying in different planes and arranged to coact with the rear wall and marginal flanges of the retaining groove to exert spring pressure, whereby the partition may be locked 110 in any desired position of adjustment.

5. In a structure of the character described, a section for the reception of articles to be displayed provided with a retaining groove extending longitudinally at the back of said section, vertical partitions each equipped with a base adjustably engaged in said retaining groove, said partitions being formed with a slot adjacent the 125 130

top front corner of each, and a rod secured to the sides of the section and engaging said slots in the partition.

6. In a structure of the character described, a section for the reception of articles to be displayed, vertical partitions adjustably secured in said section, said partitions being each formed with an inclined slot extending downwardly and forwardly from the top edge of the partition at a point near the top front corner thereof, and a rod secured to sides of the section and engaging said slots in the partition.

7. In a structure of the character described, a horizontal casing section arranged for the reception of articles to be displayed, removable vertical partitions horizontally adjustable in said section, and a rod engaging each partition adjacent its top front corner for retaining contained articles within the compartments between the partitions.

8. In a structure of the character described, a casing section provided with a longitudinal retaining groove formed with

marginal overhanging flanges, and a partition formed with a base portion arranged to engage along two opposite edges beneath said flanges and also formed with a connecting neck portion, said base being bent along a line parallel with one engaging edge. 25

9. In a structure of the character described, a horizontal casing section provided with a longitudinal retaining groove formed with marginal overhanging flanges, and vertically arranged adjustable partitions each formed with a base portion arranged to engage at its top and bottom beneath said flanges and also formed with a connecting neck portion, one corner of the base adjacent the neck and the diagonally opposite corner being both diagonally 30 clipped, and the portion of the base along one horizontal margin being bent forwardly. 35
